UNITED STATES PATENT OFFICE

146,488

DESIGN FOR A FISH LURE

Jay E. Short, Delta, Ohio

Application February 12, 1946, Serial No. 126,516

Term of patent 7 years

(Cl. D31—4)

To all whom it may concern:

Be it known that I, Jay E. Short, a citizen of the United States and resident of Delta, in the county of Fulton and State of Ohio, have invented a new, original, and ornamental Design for a Fish Lure, of which the following is a specification, reference being had to the accompanying drawings, forming a part thereof.

In the drawings:

Fig. 1 is a top plan view of a fish lure showing my new design, and Figs. 2, 3 and 4 are side, front and rear end views thereof.

The dominant features of the design reside in the portions shown in full lines.

I claim:

The ornamental design for a fish lure, substantially as shown and described.

JAY E. SHORT.
